(57) **CLAIM**

The ornamental design for a portable electronic device, as shown and described.

DESCRIPTION

FIG. 1 is a front, top, and right side perspective view of a portable electronic device;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a front elevational view thereof, depicted in a closed state;

FIG. 9 is a rear elevational view thereof, depicted in a closed state;

FIG. 10 is a right side elevational view thereof, depicted in a close state;

FIG. 11 is a sectional view thereof, taken along line 11-11 in FIG. 2 of the portion of the bottom plan view indicated by line 1101-1101 in FIG. 5; and,

FIG. 12 is an enlarged section view thereof, taken between lines 1201-1201 and 1202-1202 in FIG. 11.

The broken lines in the drawings show portions of the portable electronic device that form no part of the claimed design.

1 Claim, 12 Drawing Sheets
